Primary Examiner — Rachel A. Voorhies

(57) **CLAIM**

The ornamental design for a portion of a computer screen with a graphical user interface, as shown.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front elevation view of a portion of a computer screen with a graphical user interface depicted in various colors.

The broken lines in the drawing are included to illustrate environment only and form no part of the claimed design. The outermost broken lines show a portion of a computer screen that forms no part of the claimed design. The remaining broken lines show portions of the graphical user interface that form no part of the claimed design.
